Primary Examiner — Michael C Stout*Assistant Examiner* — Katrina N Gonzalez(74) *Attorney, Agent, or Firm* — Husch Blackwell LLP(57) **CLAIM**

The ornamental design for a megaphone bell, as shown and described.

DESCRIPTION

FIG. 1 is a perspective view of a megaphone bell showing my new design;

FIG. 2 is a front elevation view thereof;

FIG. 3 is a right side elevation view thereof, the left side being a mirror image;

FIG. 4 is a top plan view thereof; and,

FIG. 5 is a bottom plan view thereof.

The dash-dash type broken lines shown in the drawing views are included for the purpose of showing environmental subject matter that forms no part of the claimed design.

1 Claim, 3 Drawing Sheets(56)
